UNITED STATES PATENT OFFICE.

ERIK GUSTAF LARSON, OF GOTENBORG, AND JOHAN TEODOR SÖDERSTRÖM, OF KATRINEHOLM, SWEDEN, ASSIGNEES TO AKTIEBOLAGET SVENSKA KULLAGER-FABRIKEN, OF GOTENBORG, SWEDEN, A CORPORATION OF SWEDEN.

METHOD OF FORMING THE RIM MEMBERS OF SHEET-METAL PULLEYS.

1,366,671.

Specification of Letters Patent. Patented Jan. 25, 1921.

Application filed August 21, 1919. Serial No. 318,993.

To all whom it may concern:

Be it known that we, ERIK GUSTAF LARSON and JOHAN TEODOR SÖDERSTRÖM, subjects of the King of Sweden, residing, respectively, at Gottenborg, Sweden, and at Katrineholm, Sweden, have invented a new and useful Improvement in Methods of Forming the Rim Members of Sheet-Metal Pulleys, of which the following is a specification.

The present invention relates to a method of producing a convex or curved profile of the rim member of sheet metal pulleys. The face or periphery of pulleys has as a rule a convex profile in order to prevent the belt from slipping off. The present invention relates to a simple method of producing such convex profile of the face or periphery of sheet metal pulleys in which the rim member consists of a sheet metal band placed around a spider or spoke member.

The present method is broadly characterized by this that the band which is to form the rim, is introduced between a punch and a corresponding die and is pressed and successively fed between said punch and said die so that owing to the pressing the band obtains the desired convex profile. In practice the said pressing may be performed on rim members the ends of which are butt-jointed, as well as on rim members which are provided at the joint with flanges bent inward for securing the rim member to the spider or spoke member. In the first named instance the metal band is first bent so that it obtains the proper curvature corresponding to the diameter of the pulley, which bending may be effected for instance in a rolling apparatus having three rolls the upper one of which is adjustable. The band is afterward fed between the punch and the die for producing the convex profile. On the other hand, if the rim member is provided with jointing flanges bent inward, it is suitable, before the rim member is pressed to convex profile, to corrugate or slit the said flanges so that they permit the portions of the rim member adjacent said flanges to acquire the convex profile. If the jointing flanges are plaited or corrugated and thus not slit this operation will produce a certain arching of the rim member in the vicinity of the flanges. When the jointing flanges have been made corrugated the sheet metal

band is bent to the proper curvature in a 55 rolling apparatus of the kind above referred to, and is afterward introduced into the pressing means and is pressed to convex profile by successive feeding by hand. Such stresses which may be produced by this final 60 pressing will be taken up by the corrugations.

Accordingly, the complete method for producing a rim member with jointing flanges comprises the cutting of a metal plate 65 or band to proper size, bending of its ends at right angles to form such flanges, then slitting or corrugating the flanges; bending the metal into approximately the segment of a cylinder preferably after such formation 70 of the flanges; and finally pressing the convex portion of the rim member to impart to it a profile which is convex in a plane coincident with the axis around which the pulley is to turn.

The means for pressing the rim member to the desired convex profile consists principally of a punch and a corresponding die the working surfaces of which punch and die have the same curvatures in the central 80 plane of the rim member as the inner and outer surfaces of the mounted rim member, while in the axial plane they have greater curvatures than the desired convex profile of the rim member. This latter feature is 85 necessary since after the pressing the rim member always flattens out somewhat owing to the elasticity of the material. The means for plaiting or corrugating the jointing flanges consists suitably in similar manner 90 of a punch and a die one of which is provided with one or more preferably wedge-shaped projections and the other of which is provided with one or more correspondingly shaped grooves.

The accompanying drawings illustrate by way of example one embodiment of the first-mentioned means and one embodiment of the last mentioned means. Figure 1 shows a side view of the means for producing the convex 100 profile of the rim member, and Fig. 2 shows an edge view of the said means. Fig. 3 shows a side view of the means for producing the corrugations.

The means for producing the convex profile consists of the punch 1 and the corresponding die 2. The punch 1 is provided with a groove 3 in order to provide against

pressing down of guiding knobs which are preferably provided in the rim member for guiding said member on the spider or spoke member. Otherwise the punch has the shape of two cones the bases of which abut. The curvatures of the punch and of the die in the central plane of the rim member are equal to the desired curvatures of the inner and outer surfaces of the rim member 4, whereas the concave angle between the bounding lines in the axial plane of the rim member is slightly smaller than the desired angle, in view of the elasticity of the material.

If desired, the punch 1 may, of course, be shaped in such manner that the section of the punch in a plane through the axis of the rim member is bounded by a circular curve instead of two straight lines, as shown in Fig. 2. The radius of said circular curve shall in such case be somewhat smaller than the radius of the final curvature.

The means for corrugating shown in Fig. 3 consists of a punch 5 and a die 6. The punch 5 is adjustable in lateral direction and is provided in the working surface directed toward the die with a semi-circular or wedge-shaped projection 7, which is largest at the bottom and tapers into a point at the upper edge of the working surface. The die 6 is provided with a groove 8 corresponding to the projection 7. The punch 5 is secured to a reciprocating slide-block 9 which is guided in a guide 10. The movement of the slide-block toward the die is produced by means of a wedge 11 which is movable in vertical direction and bears against a roller 12 journaled in the slide block. A coil spring 14 is inserted between the slide-block 9 and the portion 13 of the guide 10 supporting the die 6, which spring becomes compressed when the slide block is moved against the die and moves the slide-block back to initial position when the wedge 11 moves upward.

The rim member 15 is placed over the portion 13 so that its flange 16 covers the working surface of the die 6. When the punch is moved against the flange the desired corrugation is formed in said flange, and simultaneously, the portion of the rim member adjacent the flange obtains a slightly convex or arched shape. When the flange has been corrugated the rim member is bent to the proper curvature and is finally pressed with the apparatus shown in Figs. 1 and 2, so that it obtains the desired convex shape.

It will be understood that the punch 5 may also be provided with several projections 7 adjacent one another and the die 6 with a corresponding number of slots 8, so that several plaits or corrugations are formed in the jointing flanges.

We claim:

1. The method of forming the rim mem-

ber of sheet metal pulleys which consists in turning up the ends of metal bands to form jointing flanges, and convexing the intervening portions of the bands by repeated pressure between a punch and die having at their junction a convex profile, such profile being a segment of a circle in the plane of the pulley, and being of convex section in planes coinciding with the axis of the pulley.

2. The method of forming the rim member of sheet metal pulleys which consists in convexing a metal band having its ends bent to form jointing flanges by subjecting it between such flanges to pressure between a punch and die having at their junction a convex profile, such profile being a segment of a circle in the plane of the pulley, and being of convex section in planes coinciding with the axis of the pulley, such pressure being applied repeatedly to different portions of the band.

3. The method of forming the rim member of sheet metal pulleys which consists in turning up the ends of a metal band to form jointing flanges, shaping such flanges so as to not oppose the convexing of the contiguous portions of the band in a transverse plane, and then convexing the intervening portions of the band by pressure between a punch and die having at their junction a convex profile, such profile being a segment of a circle in the plane of the pulley, and being of convex section in planes coinciding with the axis of the pulley, such pressure being applied repeatedly to different portions of the band.

4. The method of forming the rim member of sheet metal pulleys which consists in turning up the ends of a metal band to form jointing flanges, then corrugating such flanges so that they will not oppose the convexing of the contiguous portions of the band in a transverse plane, and then convexing the intervening portions of the band by pressure between a punch and die having at their junction a convex profile, such profile being a segment of a circle in the plane of the pulley, and being of convex section in planes coinciding with the axis of the pulley, such pressure being applied repeatedly to different portions of the band.

5. In the forming of the rim member of sheet metal pulleys by first turning up the ends of a metal band to form jointing flanges, and then convexing the intervening portions of the band, the step of corrugating such flanges by pressing them between corrugating dies adapted to crimp the flanges to a depth continually increasing from the bend to the end of each flange.

ERIK GUSTAF LARSON.
JOHAN TEODOR SÖDERSTRÖM.
